UNITED STATES PATENT OFFICE.

WILLIAM E. MOORE AND FRANK R. CLARK, OF AUGUSTA, GEORGIA.

WEFT-REPLENISHING LOOM.

SPECIFICATION forming part of Letters Patent No. 704,485, dated July 8, 1902.

Original application filed April 3, 1900, Serial No. 11,315. Divided and this application filed July 27, 1900. Serial No. 25,029. (No model.)

To all whom it may concern:

Be it known that we, WILLIAM E. MOORE and FRANK R. CLARK, citizens of the United States, residing at Augusta, in the county of 5 Richmond and State of Georgia, have invented certain new and useful Improvements in Weft-Replenishing Looms; and we do hereby declare the following to be a full, clear, and exact description of the invention, such as 10 will enable others skilled in the art to which it appertains to make and use the same.

Our invention relates to improvements in looms, and especially to that class of looms in which the bobbins are automatically supplied to the shuttle when the weft or filling 15 is practically exhausted or broken.

The present application is a division of the application for improvements in looms filed by us April 3, 1900, serially numbered 11,315, 20 and patented May 21, 1901, No. 674,632, and has reference especially to the improved means for controlling the action of automatic filling-changing mechanism by electric circuits operated either upon the practical exhaustion or breaking of the filling. 25

In addition to the above feature the present invention embodies other features and combinations of parts operated in connection therewith, all of which will be fully described, 30 and pointed out in the claims.

Referring to the drawings which illustrate our invention, Figure 1 represents in end elevation and partly in section a loom with our invention attached thereto, only so much of 35 the loom being shown as is necessary to illustrate the principle of the invention. Fig. 2 represents in elevation, slightly enlarged, the detent mechanism for operating the bobbin-feed magazine. Fig. 3 represents a fragmentary side elevation of a loom provided with our invention, portions being omitted for the sake of clearness in the drawings. Fig. 4 represents a top plan view of the said 40 loom and attachments, showing the electric circuits in diagram. Fig. 5 represents an enlarged detail view of the electrically-operated filling-fork mechanism. Fig. 6 represents an enlarged detail view, in front elevation, of one of the retainers for holding the head of the 45 bobbins in the magazine, and Fig. 7 represents a vertical central section of the same. 50

Fig. 8 represents an enlarged fragmentary elevation of the sprocket-chains of the magazine and rods connecting them together. Fig. 9 represents in enlarged side elevation 55 one of the retainers for engaging the toe of the bobbin and provided with a thread-end holder, and Fig. 10 represents a vertical central section of the same. Fig. 11 represents an enlarged detailed view, partly in elevation and partly in section, of one end of a shuttle and bobbin carried thereby, showing the system of electrical contacts by which the empty bobbin is detected. Fig. 12 represents a top plan view of the same. Fig. 13 represents the head of a bobbin in elevation provided with a metallic ferrule, which is shown in section. Fig. 14 represents a plan view of the bottom of one end of the shuttle, showing the metallic contact-maker carried thereby; 70 and Fig. 15 represents a top plan view of one end of the shuttle and shuttle-box, showing in dotted lines the position of the electrical contact-pieces employed in completing the circuit to the electromagnetic magazine mechanism at such times only as the shuttle is in 75 the proper position to receive a new bobbin.

Similar characters refer to similar parts throughout the several views.

A represents the frame of a loom of any 80 approved form, B the lay, and C C' the shuttle-boxes, having the usual shuttle-binders c c'. The lay B, carried by the swords b, is rocked in the usual manner from the crank-shaft b'. The bobbin - magazine feed mechanism is 85 mounted upon a frame A', secured to one of the loom end frames, as shown, and comprises, among other parts, two sprocket-wheels D, mounted to rotate upon a shaft d, which is secured fast to the frame A'. A second shaft 90 d' is rotatably mounted in the lower portion of the frame A' and carries two sprocket-wheels D', the outer end of the shaft d' being journaled in a supporting-frame A², secured to the frame A', as shown, or cast integral 95 therewith, as preferred. The wheels D and D' are geared together by sprocket-chains E E'. In order to secure greater rigidity, these chains may be connected by rods E², as shown in Fig. 8. To every alternate outer link of 100 the chain E is secured a bobbin-retainer e, which is adapted to hold the head of the bob-

bin, and consists of a metallic plate bent once upon itself, (see Figs. 6 and 7,) one of the members e' being adapted to engage the end of the bobbin and is provided with the button-shaped lug e^2 , which fits into the hollow end of the bobbin, while the member e^3 is concave at its upper end engaging the side of the head of the bobbin, the purpose of which is to prevent the bobbin from being pushed out in the wrong direction by the shuttle when the change of bobbins is taking place, as will hereinafter more fully appear. The retainers e are provided with screw-holes e^0 for attaching them to the chains. The corresponding alternate outer links of the chain E' carry the combined retainers and thread-end holders, which hold the other ends of the bobbins and which consist of a metallic strip e^4 , provided near its upper end with a cavity e^5 , into which the end of the bobbin fits. (See Figs. 9 and 10.) The lower end of the strip is bent upward upon itself and then outward and upward, forming an arm e^6 , which constitutes the thread-end holder to which the thread or filling E' is secured. Between each pair of these retainers is carried a filled bobbin F , (see Fig. 3,) where two bobbins are shown in the magazine, the rest being omitted for the sake of clearness in the drawings. The other bobbin-holders are also omitted from Figs. 3 and 4 for the same reason. The bobbins in the magazine are brought successively into the feeding position and held there for the proper length of time by the electromagnetically-operated ratchet and detent mechanism. (Shown most clearly in Figs. 2 and 3.) This mechanism comprises, among other parts, the electromagnet G , secured to the frame of the loom, as shown, and having an armature g , secured to an arm g' , which is pivoted at one end to the loom-frame, as at g^2 . The other end of the arm g' is pivoted to a rod g^3 , which is in turn pivoted at its upper end to an arm g^4 , loosely secured at one end to the shaft d' . This arm g^4 carries a pawl g^5 , which engages a ratchet-wheel g^6 , mounted fast on the shaft d' . The arm g' and rod g^3 are pivoted, as at g^7 , to a rod or link g^8 . An arm g^9 is pivoted, as at g^{10} , to the frame A' , and at its other end to the upper end of the rod g^8 , where it is also pivoted to an arm g^{11} . The arm g^{11} is pivoted at its other end, as at g^{12} , to a detent-lever g^{13} , which is pivoted at its upper end, as at g^{14} , to the frame A' . The lower end of the detent-lever is provided with a lug d^{15} , which engages the teeth of a detent-wheel g^{16} , mounted fast on the shaft d' . The arms or members g^9 and g^{11} form a toggle-joint, which is normally held in the position shown in Fig. 2 by a coil-spring g^{17} , mounted on the arm g^{18} , and secured at one end to said arm and at the other to the end g^{10} of the member g^9 .

H represents a self-threading shuttle having the bobbin-retaining springs h , provided with the transverse grooves h' , which are adapted to engage the rolled threads or beads

i' on the head of the bobbin I , as hereinafter more fully described.

Secured to the bolt h^2 , which holds the springs h and countersunk into the shuttle is a metallic contact-plate h^3 , the portion h^4 of which is flush with the face of the shuttle, so that it will be seen that there is a continuous electrical connection from the plate h^3 through the bolt h^2 and springs h to the head of the bobbin, which is provided with a metallic ferrule i , having the formed threads or beads i' .

Countersunk in race-iron J are two metallic contact-springs $j j'$, placed beside each other, while in the race-iron at the other end of the lay are similarly mounted the metallic contact-springs $j^2 j^3$. These contact-springs normally extend slightly above the surface of the race-iron, so that when the shuttle has reached the extremity of its travel in either direction the plate h^3 , carried by the shuttle, will make contact with the springs $j j'$ or $j^2 j^3$, dependent upon which end of the lay the shuttle is at that time. The contact-spring j^2 is electrically connected to one of the poles of a battery or other source of electricity K , while the other spring j^3 is electrically connected to the insulated metallic contact-spring L , mounted on the breast-beam M of the loom. (See Fig. 5.) The spring-contact L is adapted to make contact at certain times, hereinafter described, with a metallic contact-piece L' , carried by the shaft N . The contact-piece L' is electrically connected with the electromagnet G , which is in turn connected to the source of electricity or battery K , (see Fig. 4,) where the electric circuits are indicated by dotted lines. A second electric circuit passes from the battery K through the coils of the electromagnet G , and thence to an insulated metallic contact-spring O and through a second insulated contact-spring O' , mounted close to the spring O and then to an insulated metallic contact-spring P , and mounted near this spring P is an insulated metallic contact-spring P' , which is electrically connected to the battery K . The electric circuit is completed through the springs P and P' at the proper time by the boss Q , mounted on the shaft Q' , (see Fig. 1,) which boss engages the spring P' and causes it to make contact with the spring P , while the circuit is completed through the contact-springs O and O' by the bobbin-retainers e , which as they come into the feeding position strike the spring O and cause it to contact with the spring O' .

The means for detecting an empty or almost empty bobbin and operating the magazine so as to supply a filled bobbin to the shuttle after the filling has become nearly exhausted comprises, among other parts, a feeler R , which consists of a metallic spring located at the right-hand end of the loom and secured fast to the frame A^3 , or otherwise to the frame of the loom. The feeler extends into the shuttle-box C' and is so located that when the shuttle reaches the position shown

in dotted lines on the right in Fig. 4 the feeler will rest upon the filling or thread of the shuttle and will continue to rest thereon at each time that the shuttle reaches that end 5 of its travel until the filling becomes exhausted, or nearly so, when the feeler will be brought into contact with the metallic ferrule on the head of the bobbin. Electric connection will then be established from the 10 feeler through the ferrule, the retaining-springs of the shuttle, contact-plate h^3 on the bottom of the shuttle to the contact-spring j' , which latter is electrically connected to the battery K. The feeler R is preferably 15 insulated from the loom-frame, but is electrically connected to the coil of an electromagnet R', which is in turn connected with the battery K. The electromagnet R' is mounted fast upon the filling-fork slide r, 20 which is mounted to slide in the usual manner in the bracket r', secured to the breast-beam M. A bell-crank lever r^2 is pivoted at r^3 to the slide r. The arm r^4 of this lever forms an armature for said electromagnet, 25 while the depending arm r^5 acts as a dog, which when the magnet R' attracts the armature r^4 will engage the filling-fork hammer S, which is formed upon the end of the lever S', pivoted upon the shaft s, all of which is most 30 clearly shown in Fig. 5. The depending arm r^5 of the lever r^2 is normally held up out of the path of the hammer S by the spring r^7 . The lever S' rests upon a cam T, carried by the shaft Q', by means of which cam the desired 35 rocking motion is imparted to the filling-fork hammer S, as is well understood in the art. An eye r^6 , secured to the back of the slide r, engages the upper end of an arm n, which extends through the breast-beam 40 from the shaft N, to which it is rigidly secured. The filling-fork U is pivoted in the slide r, as at r^0 , in front of the comb V.

Assuming the magazine to be filled with 45 fresh or filled bobbins, the operation of our invention is as follows: When the filling on the bobbin in the shuttle has become exhausted, or nearly so, the feeler R will make contact with the metallic head of the bobbin when the shuttle has reached its right-hand 50 position. This will complete the electric circuit through the contacts j' and h^3 to the battery and from there through the electromagnet R'. When this takes place, the magnet R' will attract its armature r^4 and throw the 55 arm r^5 (see Fig. 5) in the path of the filling-fork hammer S, which upon its backward stroke will engage the catch of arm r^5 and move the filling-fork slide r with it. This will rock the arm n and cause the contact- 60 maker L' to engage the contact L, which will partly complete the circuit from the battery through the coils of the magnets G; but this circuit will not be entirely completed until the shuttle reaches the shuttle-box C and is in 65 the proper position there to receive the new bobbin. When it has reached that position, the contact-plate h^3 , carried by it, will com-

plete the electric circuit across the springs j^2 and j^3 . The magnet G will then become energized and draw down its armature. The effect 70 of this will be to cause the pawl g^5 to rotate the ratchet-wheel g^6 one-eighth of its revolution—that is, to a sufficient extent to bring the fresh bobbin at position 1, Fig. 1, into position 2, where the retainer is shown in dotted lines. 75 As the ratchet rotates this distance the detent-lever g^{13} rises out of the detent-wheel, but returns to it when the wheel has rotated the proper distance and engages it between its teeth, preventing it from rotating further 80 until the magnet is acted on. This motion of the detent-lever is obtained by the use of the toggle-joint at $g^9 g^{11}$, as will be readily understood. When this has taken place and the fresh-filled bobbin is in position 2, Fig. 1, the 85 lay will beat up and drive the shuttle into engagement with the bobbin, forcing the shuttle-springs over the bobbin-head and ejecting the empty bobbin, which will be pushed out by the filled one. The lay then beats back, 90 taking the filled bobbin with it, as the friction of the bobbin-springs against the bobbin-head is greater than the friction between the bobbin-retainers of the magazine and the bobbin. When the bobbin has thus been fed 95 to the shuttle, the retainers which carried it cannot, however, remain in position 2, but must be carried into position 3 just as soon as the change has been made and before the lay reaches the end of its next forward beat. 100 This is accomplished by causing each bobbin-retainer e of the magazine as it comes into position 2 to engage a contact-spring O, which will thereby be brought into contact with the spring O', which will partly complete an electric 105 circuit from the battery through the magnet G. The electric circuit is then entirely completed by the boss Q on the shaft Q' bringing the contact-spring P into engagement with the spring P'. The magnets G thus 110 become energized and operate the ratchet and detent mechanism, as before described, and send the empty bobbin-retainers into position 3. Exactly the same operation is repeated for all of the succeeding filled bobbins— 115 that is, when the filling of the one in use becomes about exhausted.

The operation when the filling becomes broken is as follows: When the filling is broken, the end u of the filling-fork, as is well 120 understood in the art, will not be lifted from the path of the filling-fork hammer S, but will be engaged by it and push the slide r back, operating the arm n and making electrical connection between the contacts L and L'. 125 This will partly complete the circuit through the magnet G, which circuit will be completed when the shuttle arrives at that position in the box C where its contact h^3 will be brought into engagement with the contact-springs j^2 130 and j^3 . This will energize the magnet G and cause a new-filled bobbin of the magazine to be brought from position 1 to position 2 and fed to the shuttle, as hereinbefore described.

The bobbin-retainers are then passed on to position 3, just as before described, by the completion of the circuit of the magnet G, through the contacts O O' and P P'.

Having thus described our invention, we do not wish to be understood as confining ourselves to the specific form and details shown and described, as many changes may be made therein without departing from the spirit of the invention.

What we claim, and desire to secure by Letters Patent of the United States, is—

1. In a loom, the combination with a filling-changing mechanism, of means for controlling the operation thereof including an electric circuit, the electric condition of which is changed upon the exhaustion of the filling in an active shuttle to a predetermined amount, and an auxiliary circuit partially completed by change in the electric condition of the first-named circuit:

2. In a loom, the combination with a filling-changing mechanism, of means for controlling the operation thereof including an electric circuit, the electric condition of which is changed upon the exhaustion of the filling in an active shuttle to a predetermined amount, an auxiliary circuit partially completed by change in the electric condition of the first-named circuit, and subsequently operating means for wholly completing said auxiliary circuit.

3. In a loom, the combination with a filling-changing mechanism, of means for controlling the operation thereof including an electric circuit the electric condition of which is changed upon the exhaustion of the filling in an active shuttle to a predetermined amount, and a second circuit completed by the said shuttle.

4. In a loom, the combination with a filling-changing mechanism, of means for controlling the operation thereof including an electric circuit the electric condition of which is changed upon the exhaustion of the filling in an active shuttle to a predetermined amount, and a second circuit completed by the said shuttle when in the changing position.

5. In a loom, the combination with a filling-changing mechanism, of means for controlling the operation thereof including an electric circuit, the electric condition of which is changed upon the exhaustion of the filling in an active shuttle to a predetermined amount, an auxiliary circuit partially completed by change in the electric condition of the first-named circuit and wholly completed by the shuttle.

6. In a loom, the combination with a filling-changing mechanism, of means for controlling the operation thereof including an electric circuit, the electric condition of which is changed upon the exhaustion of the filling in an active shuttle to a predetermined amount, an auxiliary circuit partially completed by change in the electric condition of the first-named circuit and wholly completed by the shuttle when the said shuttle is in the changing position.

7. In a loom, the combination with a filling-

changing mechanism, of means for controlling the operation thereof including an electric circuit, the electric condition of which is changed upon the exhaustion of the filling in an active shuttle to a predetermined amount, an auxiliary circuit partially completed by change in the electric condition of the first-named circuit, and means for completing said auxiliary circuit when the shuttle is in the changing position.

8. In a loom, the combination with the lay, shuttle-boxes, shuttle and filling-changing mechanism, of means for controlling the operation of said filling-changing mechanism including electric contacts carried by said shuttle-boxes, an electric circuit including a set of said contacts and having its electric condition changed upon the exhaustion of the filling in an active shuttle to a predetermined amount, a second circuit, and means for completing the same through another set of said contacts when the shuttle is in the feeding position.

9. In a loom, the combination with the lay, shuttle-boxes, shuttle and filling-changing mechanism, of means for controlling the operation of said filling-changing mechanism, including electric contacts carried by said shuttle-boxes, an electric circuit including a set of said contacts and having its electric condition changed upon the exhaustion of the filling in an active shuttle to a predetermined amount, and a second circuit completed by the closure of another set of contacts by the shuttle when it is in its changing position.

10. In a loom, the combination with an electromagnetically-operated changing mechanism, of means for controlling the operation thereof including an electric circuit, the electric condition of which is changed on the exhaustion of the filling to a predetermined amount, and an electromagnetic circuit making and breaking device in said circuit.

11. In a loom, the combination with an electromagnetically-operated filling-changing mechanism, of means for controlling the operation thereof including an electric circuit the electric condition of which is changed upon the exhaustion of the filling in an active shuttle to a predetermined amount, and an auxiliary circuit governed by the change in the electric condition of the first-named circuit.

12. In a loom, the combination with an electromagnetically-operated filling-changing mechanism, of means for controlling the operation thereof including an electric circuit the electric condition of which is changed upon the exhaustion of the filling in an active shuttle to a predetermined amount, and a second circuit completed by the said shuttle.

13. In a loom, a bobbin-magazine for automatically supplying bobbins to the shuttle, bobbins carried by said magazine, electromagnets operating to bring the bobbins of said magazine successively into the feeding position, an electric circuit passing through

the coils of said magnets, an electric circuit governing the operation of said magnet-circuit, and means for changing the electric condition of said governing-circuit upon the 5 exhaustion of the filling in an active shuttle to a predetermined amount.

14. In a loom, the combination with a filling-changing mechanism, of means for controlling the operation thereof including an electric 10 circuit, and means operated upon the breaking of the active filling for initiating the completion of said circuit.

15. In a loom, the combination with a filling-changing mechanism, of means for controlling the operation thereof including an electric 15 circuit, and means operated upon the breaking of the active filling for partially completing the said circuit.

16. In a loom, the combination with a filling-changing mechanism, of means controlling the operation thereof including an electric circuit, means operated upon the breaking 20 of the active filling for initiating the completion of said circuit, a shuttle, and means

operated by the shuttle when in the changing 25 position for completing said circuit.

17. In a loom, the combination with a filling-changing mechanism, of means controlling the operation thereof, including an electric circuit, a filling-fork, and means operated by 30 the filling-fork upon the breaking of the active filling for initiating the completion of said circuit.

18. In a loom, the combination with a filling-changing mechanism, of means for controlling the operation thereof, including an electric 35 circuit, a filling-fork, means operated by the filling-fork upon the breaking of the active filling, and partially completing said circuit, a shuttle, and means operated by the 40 shuttle for completing said circuit.

In testimony whereof we affix our signatures in presence of two witnesses.

W. E. MOORE.
FRANK R. CLARK.
